UNITED STATES PATENT OFFICE.

NORMAN J. MOONEY, OF SAN FRANCISCO, CALIFORNIA.

TOBACCO-PIPE.

1,356,388.

Specification of Letters Patent. Patented Oct. 19, 1920.

Application filed November 11, 1916, Serial No. 130,790. Renewed September 15, 1919. Serial No. 323,996.

To all whom it may concern:

Be it known that I, NORMAN J. MOONEY, a citizen of the United States, residing at San Francisco, in the county of San Francisco and State of California, have invented certain useful Improvements in Tobacco-Pipes, of which the following is a specification, reference being had therein to the accompanying drawing.

10 The invention relates to pipes, and more particularly to the class of tobacco pipes.

The primary object of the invention is the provision of a pipe of this character wherein the bowl and stem thereof are made 15 in separable sections, so that said bowl and stem can be readily cleaned, and thereby eliminate nicotin from filling the channel in the stem and thus choking the same, which would impair the draft through the 20 channel when the pipe is in use.

Another object of the invention is the provision of a pipe of this character wherein the bowl and stem are of novel form, and the said bowl carries a false bottom, thereby 25 eliminating the possibility of the burning through of the bowl when the pipe is being smoked, and also assuring the cleansing of the pipe with despatch, both in the bowl thereof and its stem.

30 A further object of the invention is the provision of a pipe of this character wherein the separable parts thereof when assembled, will not only provide a rigid structure, but will have the appearance of an ordinary one 35 piece pipe, and the draft through the pipe will not be impaired through leakage of air between the separable sections of the bowl and stem.

40 A still further object of the invention is the provision of a pipe of this character wherein the mouth piece will prevent the separation of the sections of the bowl when said mouth piece is engaged in the stem, and upon the removal of the mouth piece the sections 45 can be readily separated for the cleaning of the bowl and stem, and the removal of the false bottom from the bowl which facilitates the cleaning of the bowl and said false bottom, and avoids the charring or 50 burning of the bowl through the bottom thereof.

A still further object of the invention is the provision of a pipe of this character which is extremely simple in construction, 55 possesses few parts, which may be readily as-

sembled or disassembled, strong, durable, and inexpensive in manufacture.

With these and other objects in view, the invention will be more fully described, illustrated in the accompanying drawing, and 60 specifically pointed out in the claims which are attached hereto, and form a part of this application.

In the accompanying drawing:—

Figure 1 is a perspective view of a pipe 65 constructed in accordance with the invention.

Fig. 2 is a vertical transverse sectional view through the bowl.

Fig. 3 is a vertical longitudinal sectional 70 view through the pipe.

Fig. 4 is a vertical transverse sectional view through the stem.

Fig. 5 is a bottom plan view of the bowl and stem with the separable section re- 75 moved.

Fig. 6 is a plan view of the separable section.

Similar reference characters indicate corresponding parts throughout the several 80 views in the drawing.

Referring to the drawing in detail, the tobacco pipe comprises a body 10, which constitutes the bowl proper and has formed therewith a portion 11 of the stem, the other 85 portion 12 of which is integral with a separable bottom 13 for the body 10, constituting the bowl.

The open bottom end of the body 10, constituting the bowl and the portion 11 of the stem, is formed with a dove tail shaped groove 14, which extends longitudinally of said stem, while formed on the portion 12 and the bottom 13 is a dovetail shaped rib 15, corresponding to the groove 14, to be detachably received therein, and in this manner the bottom 13 and portion 12 are detachably locked with the body 10 to the portion 11 and this is effected on the sliding of the rib 15 into the groove 14, through either 100 end thereof.

The portions 11 and 12 of the stem are channeled at 16 to provide the draft passage longitudinally through the stem, which communicates with the body 10 interiorly 105 thereof.

The passage at the outer free end of the stem is enlarged and formed with internal threads 17 for detachably receiving a threaded nipple 18, which is slightly larger than 110

- the enlarged threaded portion of the passage, so as to spread the portions 11 and 12 on the engagement of the nipple 18 in the enlarged portion of the passage to firmly 5 clamp thereon a ring or sleeve 19, which is telescoped upon the free end of the stem, and this sleeve is formed with an internal annular shoulder 20, to limit the telescoping engagement of the sleeve 19 upon the stem.
- 10 The nipple 18 is carried in the larger end of a tapering mouth piece 21, which is also formed with the usual draft passage providing a continuation of the passage in the stem of the pipe, as usual.
- 15 Removably fitted in the open end of the body 10 is a false bottom 22, which is of substantially cup shape, and this bottom is received in a seat 23 therefor, provided interiorly in the body 10, the bottom 22 in 20 its periphery being provided with a lug 24, which is received in a notch 25 in the wall of the seat 23, so as to prevent rotation of the false bottom when held within the seat, and also to assure the registration of the 25 opening 26 in said false bottom 22 with the passage in the stem, so that direct draft will be had through the stem and mouth piece from the body 10 of the pipe.

On the removal of the mouth piece from 30 the stem of the pipe, the bottom 13 and the portion 12 can be separated from the body and portion 11, which portions 11 and 12 constitute the stem, and thus the false bottom 22 can be removed from the body 10, 35 so that both the body and the stem can be readily cleaned with despatch, and likewise the false bottom cleaned.

The pipe, with the separable parts, can be readily assembled and disassembled in a 40 convenient manner.

On the engagement of the nipple 18 in the free end of the stem, the sleeve 19 will bind upon the portions 11 and 12, as said portions are slightly spread, and in this manner the 45 separable sections of the body and stem will

be firmly locked together without possibility of the leakage of air from the draft passage on the smoking of the pipe, nor will there be any possibility of the separation of the parts of the pipe while in use, and in the 50 act of smoking the same.

From the foregoing, it is thought that the construction and manner of assembling and disassembling of the parts of the pipe will be clearly understood, and therefore, a more 55 extended explanation has been omitted.

What is claimed is:—

1. A device of the character described including a body forming the walls of a bowl and provided with a seat at its lower end 60 and also having a stem portion leading therefrom, a bottom for the body having a stem portion leading therefrom, means for securing the body and its stem and the bottom and its stem in detachable engagement, and a 65 false bottom positioned entirely within the body and removably held against the seat and supported by the bottom.

2. A device of the character described including a body forming the walls of a bowl 70 and provided at its lower open end with a seat and having a stem portion leading therefrom, a bottom for the body having a stem portion leading therefrom, the stem portions being provided with a smoke passage, the bottom and its stem portion being 75 provided with a groove, a rib formed on the bottom and its stem portion for detachable interlocking engagement with the groove, a false bottom for the body removably held 80 against the seat and supported by the bottom and further provided with an opening for registration with the smoke passage in the stem portions, and co-operative means formed on the false bottom and in the seat 85 for preventing rotary movement of the false bottom.

In testimony whereof I affix my signature.

NORMAN J. MOONEY.
